DESIGN FOR A COMBINED CHILD'S VEHICLE AND PACKAGE CARRIAGE

William T. Wade, Los Angeles, Calif.

Application August 28, 1943, Serial No. 111,018

Term of patent 7 years

To all whom it may concern:

Be it known that I, William T. Wade, a citizen of the United States, residing at Los Angeles, in the county of Los Angeles and State of California, have invented a new, original, and ornamental Design for a Combined Child's Vehicle and Package Carriage, of which the following is a specification, reference being had to the accompanying drawing, forming part thereof.

Fig. 1 is a front perspective view of a combined child's vehicle and package carriage, showing my new design.

Fig. 2 is a top plan view thereof on a somewhat reduced scale.

I claim:

The ornamental design for a combined child's vehicle and package carriage, substantially as shown.

WILLIAM T. WADE.
